SEAT FOR TRACTORS OR THE LIKE

Casimir E. Leja, Minooka, Ill.

Application February 25, 1958, Serial No. 49,796

Term of patent 14 years

(Cl. D14—6)

Fig. 1.

Fig. 2.

Fig. 3.

Fig. 4.

Fig. 1 is a perspective view of a seat for tractors or the like, embodying my new design;

Fig. 2 is a rear view thereof;

Fig. 3 is a plan view thereof; and

Fig. 4 is a front view thereof.

I claim:

The ornamental design for a seat for tractors or the like, as shown.
